UNITED STATES PATENT OFFICE.

ISAAC LIBSON, OF BROOKLYN, NEW YORK.

DESIGN FOR AN INCANDESCENT-ELECTRIC-LAMP CLUSTER.

No. 40,163.

Specification for Design.

Patented July 20, 1909.

Application filed March 31, 1909. Serial No. 487,097. Term of patent 3½ years.

To all whom it may concern:

Be it known that I, ISAAC LIBSON, a citizen of the United States, residing at Brooklyn, in the county of Kings and State of New York, have invented a new, original, and ornamental Design for Incandescent-Electric-Lamp Clusters, reference being had to the accompanying drawing, forming a part thereof.

Figure 1 is a perspective view showing the design of the cluster taken from the under

side and Fig. 2 is a perspective view of the cluster taken from the under side but at a less angle than that of Fig. 1.

I claim:—

The ornamental design for an incandescent electric lamp cluster, as shown.

ISAAC LIBSON.
